UNITED STATES PATENT OFFICE.

LUCIUS S. BIGELOW, OF HARRISBURG, PENNSYLVANIA, ASSIGNOR TO THE
N. O. HICKOK MANUFACTURING COMPANY, OF SAME PLACE.

PAPER-RULING MACHINE.

SPECIFICATION forming part of Letters Patent No. 443,065, dated December 16, 1890

Application filed June 4, 1890. Serial No. 354,195. (No model.)

To all whom it may concern:

Be it known that I, LUCIUS S. BIGELOW, a citizen of the United States, residing at Harrisburg, in the county of Dauphin and State 5 of Pennsylvania, have invented certain new and useful Improvements in Paper-Ruling Machines, of which the following is a specification, reference being had therein to the accompanying drawings.

10 This invention relates to certain new and useful improvements in paper-ruling machines.

The object of the invention is to provide such an organization of the machine that the 15 paper-carrier mechanism shall be divided into two sets or portions and such an organization of the power-transmitting mechanism that it can be arranged to operate both of these sets synchronously or one of them independently of the other in such a manner 20 that one set may continue its operation and the other be brought to a state of rest or inaction. The division of the carrier mechanism into these sets may vary as regards the 25 parts which are to constitute one set and the parts which are to constitute the other set; but the preferred line of division is to constitute the first set of the upper apron and its carrying-cords and the lower set of the lower 30 apron, its carrying-cords, and the paper-receiving-box mechanism.

Another object of the invention is to operate the paper-receiving box through and by means of the lower apron and to arrange the 35 driving parts so that the speed of the paper-receiving box will be accelerated above that of the said lower apron, whereby the paper will be rapidly gotten out of the way at the tail of the machine.

40 The invention also relates to an improved type of construction of power-transmitting mechanism which I shall term the "power fixture," whereby the mechanism for driving the upper set and the lower set may be both 45 connected with the power-pulley and whereby only the driving mechanism of the lower set may be connected with the power-pulley.

In the accompanying drawings, forming a 50 part of this specification, and on which like reference letters and numerals indicate corresponding parts, Figure 1 represents a rear view

of a portion of a ruling-machine with my improved power fixture applied thereto; Fig. 2, a detail view, in elevation, of the power-pulley and a cross-section of its shaft; Fig. 3, a partial side elevation and partial sectional view of parts of the power fixture; Fig. 4, a detail view of the clutch; Fig. 5, a side elevation of a ruling-machine with some of the parts broken away, exemplifying one organization of my 60 invention; and Fig. 6, a detail view of the carrier-cord rollers.

The frame of the machine may be of the usual or any approved type, as may also be the pens, pen-beam, and striking attachments. 65

In the drawings, the letter A refers to the ruling devices, and B and C the feed-rollers, each of which carries a gear-wheel D and E, which intermesh, so that the former drives the latter. 70

The letter F designates one of the usual idler gear-wheels, which meshes with the feed gear-wheel E and transmits motion to the smaller gear-wheel G on the arbor of the pen-cylinder H or cam-head shaft, as the case may 75 be, the respective functions of which are to support the apron adjacent to the pens and actuate the pen-beam and pens. At the rear of the machine the other supporting-roller I is mounted, while at intermediate points a 80 suitable number of supporting-rollers J and K are mounted to carry the lower side of the apron. This apron is designated L and is the upper apron. About the rollers M O P Q, supported by the frame of the machine, are 85 passed the first carrying-cords Q', said cords also passing about and pressing against the roller B, by which they are given motion in the same direction as the upper side of the apron L. At R, S, and T are other rollers for 90 carrying the second carrier-cords U, said cords having contact with the roller I, whereby they are given motion. The roller S is mounted in an adjustable box carried by brackets manipulated by a set-screw, as shown 95 at V, so that the tension of the cords may be regulated. Motion is applied to the roller B, and on such motion being transmitted to the roller C the upper apron and its first and second carrying-cords are given motion in 100 the direction of the arrows, whereby the paper is transmitted through the machine

by the first set of paper-transmitting mechanism.

I will now refer to the second set of paper-transmitting mechanisms. This consists of 5 the roller W, whose arbor carries a pulley X, which receives motion by a belt W' in the manner hereinafter to be described. About this roller and the roller Y, mounted adjacent to the roller T, the carrying-cords Z of the 10 second carrying mechanism are placed. The paper leaving the cords U is taken up by the cords Z. The line of division between the first and second sets of carrying mechanism is between these cords U and Z in the present 15 exemplification of the invention. The second set of carrying mechanism further consists of the rollers a b c, about which is placed the lower apron d, a part of the apron passing partially around and in close contact 20 with the roller W, whereby such apron is given motion. The direction of the motion of the cords Z and the lower apron is indicated by arrows.

In the lower rear part of the machine is placed 25 the receiving-box. This receiving-box is preferably of the type set forth and claimed in Letters Patent No. 346,411, dated July 27, 1886, for receiving-box for ruling-machines, issued to W. O. Hickok upon the application of Martin 30 L. Metzger and George W. Brown. This receiving-box consists of the feeding mechanism and of the receiving-box. The type and construction being fully shown in said patent need not be more fully described herein than 35 to say that the receiving-box is shown at e and the feeding mechanism at f. The latter consists, essentially, of the pulleys g and h, mounted upon shafts i and j, and of a belt k. It also consists of pulleys m and o, 40 mounted on shafts p and q, and of a belt r. Each set of aprons and each belt here named are in duplicates, so as to properly conduct the sheets of paper into the receiving-box, the sheets passing down the cords Z about the roller W, whence they are taken 45 up by the apron d and passed between the adjacent sides of the belts k and r. On the shaft q is a pulley s, as more clearly seen in the small figure under Fig. 5. This pulley 50 receives a driving-belt t, which passes about the pulley u, carried by the arbor of the roller c. In this manner the feeding-belts of the receiving-box are operated from the terminal roller of the lower apron. The pulley u being 55 larger than the pulley s the speed of the receiving-box belts is accelerated above that of the lower apron, whereby the paper is hastened in its delivery to the receiving-box, so that the sheets are rapidly gotten out of the 60 way. The crank and pitman, crank-arm, rock-shaft, and paddle (shown as a part of the receiving-box) need not be specifically set forth, since they form no part of the present invention. The description given of the 65 construction of the feeding mechanism of the receiving-box is done to enable an under-

standing of the operation of this mechanism in connection with the lower apron.

I will now refer to the mechanism by which motion received from the driving-power is transmitted so as to actuate the entire carrier mechanism of the machine synchronously, or so as to actuate the lower set of carrier mechanism independently of the upper set. In the ways 2, secured to the frame, is slidingly 70 mounted a plate 3, whose adjustments are effected by a set-screw 4 passing through a projection 5, connected with the ways and pressing against the lugs 6 on the plate 3. A screw-threaded stud projects from the frame 80 or the rear of the ways 2 through a slot 8 (shown in dotted lines in Fig. 1) in the plate 3, and receives a hand-screw 9, by which the plate is locked against accidental movement. This plate carries a box 10, in which is rigidly 85 mounted a shaft 11 and also a box 12, through which is passed an actuating-rod 13. This rod is pivotally connected with a hand-lever 14, working behind and against the sector 15. This lever and this sector are mounted at 90 that side of the machine—the right—at which the attendant usually stands. A curved plate 16 has marked on it at one end "Apron and lay-boy," at the middle portion "Entire machine," and at the other end "Off." When the 95 entire machine is to be operated, then the lever stands opposite the words "Entire machine." When the lower set of the carrying mechanism is to be operated alone, the lever 14 is adjusted to a position opposite the words "Apron 100 and lay-boy." When the machine is to be stopped, the lever is moved to the other extreme and over the word "Off," when the whole machine stops. On the shaft 11 is slidingly and revolvably mounted a collar 17, carrying prongs 18 and 19 and engaged by a bifurcated arm 20, carried by the actuating-rod 15. The shaft 11 also carries a loosely-mounted gear-wheel 21, which meshes with the gear-wheel D, already referred to. This 110 gear-wheel has openings in it, through which the prongs 18 may be projected and withdrawn to connect this gear-wheel with the driving-pulley 22 and the power-pulley 23. These pulleys are both carried by the shaft 115 11, and the latter is free to revolve thereon when disconnected from the other parts. The prongs 19 project through the openings in the pulley 22 and enter recesses in the pulley 23. These recesses are preferably beveled 120 at the mouth to effect the ready entrance of the prongs. It will now be seen that by actuating the collar 17 the pulley 23 may be allowed to run free, when the entire machine 125 will stop. It will be observed that the pulleys 22 and 23 may be connected together and the pulley 23 disconnected from the gear 21. It will further be seen that both the pulleys and the gear 21 may be interconnected, which is the fact when the parts are in the 130 position shown in Fig. 1. The operator may, therefore, run the entire machine synchro-

nously or stop the entire machine, or run the lower set of the carrier mechanism while the upper set is in a state of rest.

Among the advantages of being able to continue the motion of the lower carrier mechanism while that of the upper carrier mechanism is discontinued may be mentioned the following: Referring to Fig. 6, it will be seen that I have placed the rollers T and Y in different elevations, the latter being lower than the former. The object of this is to facilitate the delivery of the sheets of paper from the cords U to the cords Z. I have shown and described the usual pen-cylinder H. In some types of machines this cylinder is not used, but the shaft upon which it is mounted is used, and the usual cams for actuating the pen-cylinder and pens are mounted on this shaft. I have therefore referred to the gear-wheel G as being on the pen-cylinder or cam-head shaft, as the case may be.

Having thus fully described my invention, what I claim as new, and desire to secure by Letters Patent, is—

1. The combination, with the carrier mechanism of a ruling-machine divided into first and second sets, both sets together being arranged and located to extend from the receiving end to the delivery end of the machine to effect a continuous transmission of the paper, of motion-transmitting mechanism, substantially as described, connected with both of said sets, and intermediate devices to disconnect said motion-transmitting mechanism as to one set and maintain it as to the other set.

2. The combination, with the carrier mechanism of a ruling-machine divided into first and second sets, both sets together being arranged and located to extend from the receiving end to the delivery end of the machine to effect a continuous transmission of the paper, of a power-pulley, a driving-pulley, and a gear connected to the respective sets, clutch mechanism for connecting the power-pulley and driving-pulley and connecting and disconnecting the latter and the driving-gear.

3. The combination, with the carrier mechanism of a ruling-machine, said mechanism being divided into first and second sets, of motion-transmitting mechanism connected to both of said sets, and intermediate devices for alternately disconnecting said motion-transmitting mechanism as to one set and maintaining it as to the other set and for maintaining it as to both sets.

4. The combination, with the carrier mechanism of a ruling-machine, said mechanism being divided into first and second sets, of a power-pulley, a driving-pulley, and driving-gear, and clutch mechanism for alternately disconnecting said gear-wheel from said pul-

leys and said pulleys from each other and for connecting all three together.

5. The combination, with the upper apron, its cords, and driving and supporting rollers, and a lower apron, its cords, and the driving and supporting rollers, of a gear-wheel connecting with the upper driving-roller, a pulley connected with the lower driving-roller, a power-pulley, and clutch mechanism for alternately disconnecting said gear from said pulleys, connecting said pulleys together, and connecting all three together.

6. The combination, with the carrier mechanism of a ruling-machine, said mechanism being divided into first and second sets, and a receiving-box whose mechanism is operated by the lower set, of motion-transmitting mechanism connected with said sets, and intermediate devices for disconnecting the motion-transmitting mechanism from one of said sets and maintaining its connection with the other of said sets.

7. The combination, with the carrier mechanism of a ruling-machine, the said mechanism being divided into first and second sets, of a receiving-box whose mechanism is operated by said lower set by speed-accelerating mechanism and driving mechanism for said sets.

8. The combination, with a shaft, a pulley loosely mounted thereon, a driving-pulley, and a gear-wheel also mounted thereon, the latter loosely, of clutch mechanism for alternately connecting all three together and for disconnecting the gear-wheel and maintaining the connection of the pulleys.

9. The combination, with a shaft, a power-pulley loosely mounted thereon, a driving-pulley, and a gear-wheel mounted thereon, the latter loosely, of a sliding collar loosely mounted thereon and having prongs, openings in said pulleys, and gear-wheel to receive said prongs, an actuating-rod, and a lever for said collar.

10. In a ruling-machine, the combination, with the carrier mechanism divided into first and second sets, both sets together forming the carrier mechanism from the receiving to the delivery end of the machine, of the terminal roller of the first set and the first roller of the second set, located in different horizontal planes, whereby the delivery of the paper from the terminal roller of the first set to the first roller of the second set is facilitated.

In testimony whereof I affix my signature in presence of two witnesses.

LUCIUS S. BIGELOW.
